CLAIM

The ornamental design for a handheld multi-modal imaging device, as shown and described.

DESCRIPTION

FIG. 1 is a top, left side perspective view of a handheld multi-modal imaging device showing our new design.

FIG. 2 is a bottom, left side perspective view thereof.

FIG. 3 is a left side view thereof.

FIG. 4 is a right side view thereof.

FIG. 5 is a top view thereof.

FIG. 6 is a bottom view thereof.

FIG. 7 is a front view thereof; and,

FIG. 8 is a back view thereof.

The broken lines of the drawings illustrate portions of the handheld multi-modal imaging device that form no part of the claimed design.
